(21) Appl. No.: **29/139,353**

(57) **CLAIM**

(22) Filed: **Mar. 2, 2001**

The ornamental design for a pickup for an optical disc player, as shown and described.

Related U.S. Application Data

DESCRIPTION

(63) Continuation-in-part of application No. 29/107,818, filed on Jul. 12, 1999, now Pat. No. Des. 444,458.

FIG. 1 is a reference top, front perspective view of a pickup for an optical disc player showing my new design;

(30) **Foreign Application Priority Data**

FIG. 2 is a top plan view thereof;

Feb. 24, 1999 (JP) 11-4201

FIG. 3 is a front elevational view thereof;

(51) LOC (7) Cl. **14-99**

FIG. 4 is a left side elevational view thereof;

(52) U.S. Cl. **D14/217; D14/262; D14/156**

FIG. 5 is a right side elevational view thereof; and,

(58) **Field of Search** D14/156, 217,

FIG. 6 is a top, rear perspective view of a pickup for an optical disc player showing my new design.

D14/239, 260, 262, 299; 360/104, 105,
114; 369/13, 105

The even broken line showings of a pickup for optical disc player in FIGS. 2 and 6 are for illustrative purpose only and form no part of the claimed design. The dot-dash broken lines define, but are not included in, the boundaries of the claimed design.
